(57) **CLAIM**

The ornamental design for a connector, as shown.

DESCRIPTION

FIG. 1 is a front elevational view of a connector showing our new design; a rear elevational view thereof being a same image;

FIG. 2 is a right side elevational view thereof; a left side elevational view thereof being a mirror image;

FIG. 3 is a top plan view thereof;

FIG. 4 is a bottom plan view thereof; and,

FIG. 5 is a perspective view thereof.

FIG. 6 is an enlarged cross-sectional view thereof taken along the line 6-6 in FIG. 1; and,

FIG. 7 is an enlarged cross-sectional view thereof taken along the line 7-7 in FIG. 3.
